ELECTRIC WELDER

William Van Alan Clark, Jr., Marion, Philip Taber, South Dartmouth, and Richard M. Steigerwald, Marion, Mass., assignors, by mesne assignments, to the Sippican Corporation, Marion, Mass., a corporation of Massachusetts

Filed Nov. 16, 1961, Ser. No. 67,550

Term of patent 14 years

(Cl. D26—1)

FIG. 1

FIG. 2

FIG. 3

FIG. 4

FIG. 1 is a perspective view of an electric welder, showing our new design;

FIG. 2 is a top plan view of the electric welder shown in FIG. 1;

FIG. 3 is an elevational view of the right side of the electric welder shown in FIG. 1;

FIG. 4 is a front elevational view of the electric welder shown in FIG. 1;

FIG. 5 is a side elevational view of the left side of the electric welder shown in FIG. 1.

The dominant features of our new design reside in those portions shown by means of full lines in the drawings.

The portion of FIG. 5 broken away for purposes of illustration is identical with the corresponding opposite portion thereof shown in FIG. 3.

We claim:

The ornamental design for an electric welder, substantially as shown and described.
